UNITED STATES PATENT OFFICE

169,454

CHOCOLATE CONFECTION

Richard M. Palmer, Wyomissing, Pa.

Application December 30, 1952, Serial No. 22,922

Term of patent 14 years

(Cl. D82—2)

To all whom it may concern:

Be it known that I, Richard M. Palmer, a citizen of the United States of America, residing at Wyomissing, in the county of Berks and Commonwealth of Pennsylvania, have invented a new, original, and ornamental Design for a Chocolate Confection, of which the following is a specification, reference being had to the accompanying drawings, forming part thereof.

Fig. 1 is a front elevational view of a chocolate confection, in accordance with my new design.

Fig. 2 is a rear view thereof.

Fig. 3 is an end elevational view of Fig. 1 as seen from the left, and

Fig. 4 is an end elevational view of Fig. 1 as seen from the right.

I claim:

The ornamental design for a chocolate confection, as shown.

RICHARD M. PALMER.
